UNITED STATES PATENT OFFICE.

JOHN W. RHODEN, OF HOSFORD, FLORIDA.

ENTRY RECORDER.

Application filed June 30, 1922. Serial No. 572,008.

To all whom it may concern:

Be it known that I, JOHN W. RHODEN, a citizen of the United States, residing at Hosford, in the county of Liberty and State 5 of Florida, have invented certain new and useful Improvements in Entry Recorders; and I do hereby declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to admission recorders and has for an object to provide a device of improved type especially, though not exclusively adapted for recording the number of admissions to a street-car, or the 20 like.

A further object of the invention is to provide in combination with a place of admission, such for instance as the entry to a street-car, a revolving door or turn-stile with 25 improved means associated therewith for recording the number of actuations imparted to said turn-stile or door by the passing therethrough of persons.

A further object of the invention is to 30 provide in combination with some movable entry obstruction a traveling ribbon and means actuated by the movement of the obstruction for punching holes in said ribbon, one for each actuation.

35 A further object of the invention is to provide a traveling ribbon recording mechanism with means for advancing the same with a step by step movement, and improved mechanism for insuring uniformity of travel 40 to the ribbon, so that punch marks appearing thereon may be accurately enumerated by applying the ribbon to a scale properly calibrated or by calibrating the ribbon itself.

45 A further object of the invention is to provide, in combination with a manually rotatable part, a ribbon with means for advancing the ribbon with uniform step by step movement at each actuation of the rotating part, and means actuated at the termination of the manual movement for punching a perforation in the ribbon.

With these and other objects in view the invention comprises certain novel parts, 50 elements, units, combinations and functions,

as disclosed in the drawings, together with mechanical equivalents thereof, as will be hereinafter more fully described and claimed.

In the drawings:

Figure 1 is a top plan view of the mechanism of the recorder with the top of the casing removed;

Figure 2 is a view of the mechanism in edge elevation with the housing removed, 65 as indicated by line 2—2 of Figure 1;

Figure 3 is a horizontal sectional view through the mechanism taken on line 3—3 of Figure 2 with the part positioned as at the complete unwinding of the ribbon;

Figure 4 is a view in edge elevation of a part of the mechanism taken on line 4—4 of Figure 1;

Figure 5 is a detail vertical sectional view through the punch mechanism taken on line 70 5—5 of Figure 3;

Figure 6 is a view in edge elevation of the punch mechanism, as indicated by line 6—6 of Figures 1 and 2;

Figure 7 is a view partly in section and 80 partly in elevation of a conventional structure intended to represent a street or other car, with the device applied thereto in one approved manner.

Like characters of reference indicate corresponding parts throughout the several views.

The entrance recorder which forms the subject matter of this application is adapted for location in a great variety of places and positions and for recording entries for 90 a great variety of purposes. One of the principal uses for the device will be found in street and trolley cars and the drawing discloses it in connection with such a structure, although it is to be understood that the showing of the device associated with such structure is no limitation upon its use or utility.

In the drawings, therefore, a conventional street-car is shown at 10 with the device 100 shown therein comprising a revolving door 11 having a foot bearing 12 and a pintle 13 at the top extending upwardly through the bottom 14, upon which the device is erected. This bottom or base 14 is provided with a housing 15 of any approved shape and material and shown here as constructed of sheet metal with rounded corners, but it is to be understood that this shape of 105 construction or material is not essential to 110

the invention. In one side of the housing a sight opening is provided having a transparent closure 16 which performs only the function of disclosing when the device is 5 properly functioning.

Located within the housing 15 and upon the upper end of the pintle 13 are two disks 17 and 18, the disk 17 being provided with a plurality of notches 19 about its perimeter, while the disk 18 is provided with a like number of eccentric cams 20 having shoulders 21 arranged substantially as radii of the disk. As will be noted, the pintle 13 is squared or arranged in such manner as 10 to form rigid and permanent connections with the disks 17 and 18, so that said disks rotate with said pintle and therefore with the revolving door 11. As indicated at Figure 7 the revolving door is provided with 15 four leaves 16, but it is to be understood that the number of leaves of the door so indicated is only for convenience of illustration and that the number may be any number found desirable. The disks 17 and 20 25 are, therefore, provided with a like number of notches 19 and cams 20 and while shown as four in the drawing, it is to be understood that this is only to correspond to the number of leaves in the revolving 30 door 11 and that the door 11 with a greater or less number of leaves will call for a like increase or decrease in the number of notches and cams in the disks 17 and 18.

Adjacent the pintle 13 and the disks 17 35 and 18 a plunger 22 is mounted to reciprocate in a bearing 23 and a spring 24 is provided bearing against a collar 25 rigid upon the plunger 22 and against the abutment 26 tending to hold the plunger yieldingly in engagement with the cam surfaces 40 20 of the disk 18.

The abutment 26 is orificed, as indicated at 27 at Figures 3 and 5 and a perforating point 28 is carried by an arm 29 integral 45 with or rigidly secured to the collar 25 and so positioned that as the plunger 22 reciprocates the penetrating point will move from full line position shown at Figure 5 to dotted line position shown at said figure and to 50 periodically return to full line position to perforate the traveling ribbon 30. It will be noted that this traveling ribbon 30 passes over the front of the abutment 26 and across the orifice 27 and in its passage over rollers 55 31 and 32. The roller 31 is preferably covered upon its exterior surface with some traction-increasing material indicated at 33, which may be of rubber or any such material and the ribbon 30 is held in intimate engagement 60 therewith by a spring-pressed idler 34. The manner of applying the tension to the idler 34 is immaterial to the present invention, but a convenient and approved manner is by journaling said idler upon an arm 35, 65 which said arm is pivoted at 36, and a spring

37 employed to hold said idler 34 in engagement with the ribbon 30 passing about a segment of the perimeter of the roller 31. To actuate said roller with a step by step movement and, therefore, advance the ribbon 70 30 with a uniform movement, a ratchet 38 is mounted rigidly upon the roller 31 and a pawl 39 is pivoted at 40 upon the plunger 22 with a spring 41 for holding said pawl in engagement with the perimeter of the ratchet 38. It will be obvious that as the plunger 22 reciprocates it will, by engagement of the pawl 39 with a ratchet 38, advance said ratchet with a step by step rotary movement. 75 80

For carrying the ribbon 30 a spool 42 is mounted upon a pintle 43 and a hub 44 provides means for accommodating the ribbon wound thereon to substantially fill said spool initially, as indicated at Figure 1. 85

The pintle 43 is mounted upon a block 45 which is in turn mounted to slide between guide-ways 46 and a spring 47 is provided tending to hold the pin 48 carried by said block 45 in engagement with the notch 49 of the latch 50. The latch 50 is mounted to reciprocate in guides 51 and a spring 42 is provided tending to throw said latch 50 into engagement with one of the notches 19 of the disk 17 when released by the movement of the block 45, as indicated at Figure 3. This movement is brought about by the fact that the ribbon 30 is connected with the hub 44 in any approved manner, as by the hook 53 in such manner that when the ribbon is wholly unwound from the hub 44 the continued movement of the ribbon in its direction of unwinding, being also in the direction of the movement of the block, the tension of the spring 47 will move said block out of its engagement with the latch 50, permitting said latch, under the stress of the spring 52, to engage the perimeter of the disk 17 and the first of the notches 19 which come into position for engagement therewith. 90 95 100 105 110

To take up the ribbon as it passes over the roller 31 a spool 54 is also provided, having a pulley 55 over which a slip-belt 56 passes from the pulley 57, moving as a unitary structure with the roller 31. 115

The operation of the device is initiated by the placing upon the pintle 43 a spool of unperforated ribbon 30 and passing the end of said ribbon about the idle roller 32 across the abutment 26 in front of the perforation 27 over the feed roller 31 and under the idler 34 and connecting the end with the hub of the take-up spool 54. 120

The device is now in position to operate and as each person passes through the revolving door of the type indicated in the drawing the door will be rotated one-quarter of a revolution, or such portion of a revolution as an entire revolution divided by the 125 130

leaves of the door, or turn-stile. The revolution of the door through a segment of rotation will rotate the disk 18 through a like segment in the direction indicated by the arrow in Figure 1. This rotation will cause the plunger 22 to ride up the incline on the cams 20 until the disk has passed the point permitting the plunger to drop over the shoulder 21. While the plunger 22 is advancing by riding up the incline on the cam 20 it causes the pawl 39, in engagement with the ratchet 38, to rotate the feed roller 31 a step advancing the ribbon in the direction indicated by the arrows over and across the perforation 27. When the cam 21 has moved through its entire arc of movement, the plunger 22 will drop over the shoulder 21 and under the action of the spring 24 will cause the perforating point 28 to perforate the ribbon 30, passing through the ribbon and into the orifice 27. It also causes the pawl 39 to draw back one step in position to engage the next tooth of the ratchet 38. The rotation of the feed roller 31, as indicated, causes the ribbon 30 to move forward a uniform distance with each step by step movement of said roller and the ribbon is taken up on the take-up spool by reason of the drive of said spool through the movement of the slip-belt 56. This operation is continued once for each person passing through the door until the period of use is ended, whereupon the ribbon is removed from the housing and the number of perforations counted or otherwise calculated.

If it should so happen that the period of use should extend over such a period that the strip does not number sufficient length to accommodate all of the perforations, the final result will be the drawing of the spool 42 and block 45 to release the latch 50, which will engage one of the notches 19 and thereby lock the door against further movement. In this position it is obvious that the further use of the device will be impossible until a new roll of ribbon has been put in position and the device re-set manually to engage the latch 50 by the pintle 48.

50 What I claim is:

1. An entry recorder comprising a rotating obstruction, a cam rotated by the rotating obstruction, a plunger reciprocated by the rotating cam, a ribbon, spools carrying the ribbon, means actuated by the plunger for winding the ribbon from one spool to the other with a uniform step by step progression, and means carried by the plunger for perforating the ribbon at each reciprocation of the plunger.

2. An entry recorder comprising a rotating obstruction, a disk rotated by the obstruction and provided with a plurality of

perimetrical cams, a reciprocating plunger positioned substantially as a radius of the disk, and held in yielding engagement with the perimetrical cams, spaced spools, a ribbon passing from one spool to the other, an orificed abutment positioned to accommodate the moving ribbon, means actuated by the reciprocation of the plunger for winding the ribbon from one spool to the other with a uniform step by step progression, and means carried by the plunger co-acting with the abutment for perforating the ribbon at uniform intervals.

3. An entry recorder comprising a rotating obstruction, a ribbon, spools carrying the ribbon, means actuated by the rotation of the obstruction for winding the ribbon from one spool to the other, and means to lock the movement of the obstruction when the ribbon has been exhausted from the storage spool.

4. An entry recorder comprising a rotating obstruction, a storage spool and a take-up spool, a perforating mechanism, a ribbon passing from the storage spool by the perforating mechanism to the take-up spool, means actuated from the rotation of the obstruction to operate the take-up and the perforating mechanism, a latch for the rotating obstruction, means associated with the storage spool for holding the latch normally inoperative, and means connecting the terminal of the ribbon with the storage spool tending to move said storage spool to release said latch.

5. An entry recorder comprising a rotating obstruction, a disk rotating with said rotating obstruction and provided with a plurality of perimetrical notches, a second disk rotating with said rotating obstruction and provided with a like number of eccentric cams, spaced ribbon spools, a ribbon carried by the spools, a plunger mounted in engagement with the cams adapted to reciprocate at the movement of each cam relative thereto, means carried by the plunger for advancing the take-up spool with a step by step movement, means carried by the plunger for perforating the ribbon at each reciprocation, a latch positioned to engage the notches of the notched disk, a sliding mechanism journaling the storage spool, means carried by the sliding mechanism for engaging the latch to hold it normally inoperative, and means connecting the terminal of the ribbon with the storage spool tending to move the sliding mechanism to release the latch at the exhausting of the ribbon from the storage spool.

In testimony whereof I hereunto affix my signature.

JOHN W. RHODEN.
